UNITED STATES PATENT OFFICE.

MICHAEL M. MAHER, OF EAST LIVERPOOL, OHIO, ASSIGNOR OF ONE-HALF TO CHARLES A. SMITH, OF CHESTER, WEST VIRGINIA.

COMPOUND DOUBLE-ACTING EXPLOSIVE-ENGINE.

No. 898,243.

Specification of Letters Patent.

Patented Sept. 8, 1908.

Application filed August 29, 1907. Serial No. 390,640.

To all whom it may concern:

Be it known that I, MICHAEL M. MAHER, a resident of East Liverpool, in the county of Columbiana and State of Ohio, have invented 5 certain new and useful Improvements in Compound Double - Acting Explosive - Engines, of which the following is a specification.

This invention relates to an explosive engine, and one object is to provide for compounding the explosive charges by passing the same into a low pressure cylinder, the same being retained in the high pressure cylinder during the greater portion of the explosion stroke, thereby utilizing practically 10 all the energy available in that cylinder and at the same time making use of considerable energy which otherwise would be wasted, and also reducing the pressure which would otherwise be encountered by the piston on its exhaust stroke.

A further purpose is to provide a double acting explosive engine wherein explosive charges are adapted to operate on the piston at each end of the cylinder.

These and other objects of the invention are fully described hereinafter and claimed, and illustrated by the accompanying drawings, wherein

Figure 1 is a top plan view, partly in section, of the improved engine. Fig. 2 is a side elevation of the high pressure portion of the engine and valve mechanism associated therewith, portions thereof being shown in section. Fig. 3 is a cross sectional view, enlarged, 30 taken on line 3—3 of Fig. 1, and Fig. 4 is a similar view taken on line 4—4 of the same figure. Figs. 5 and 6 are detail views of the group of cams for operating the outlet valve of the explosion cylinder, and Fig. 7 is a diagrammatic view of the same. Fig. 8 is a detail view of part of the governor mechanism.

Referring to the drawings, 2 designates the main or explosion cylinder and 3 the fixed heads thereof. Piston 4 of this cylinder is 45 preferably constructed with the two separated heads 5 mounted on piston rod 6. The explosive charges never reach the space between these heads, and hence opportunity is afforded for lubricating the cylinder and piston, this being accomplished by a lubricator 7 which opens into the center of the cylinder, and which on the extreme movements of the piston is covered by one or the other of heads 5, the lubricator never being exposed to the

outer or active faces of the heads. As the 55 piston moves from one extreme position to the other the lubricant may enter the cylinder between the heads, and thus both the cylinder and piston are effectively lubricated without exposing the lubricator to the fire of 60 the explosions.

Within each end of cylinder 2 is a supplemental head 78 which may be adjusted either inward or outward by screws 79 in cylinder heads 3. By means of these supplemental 65 heads the clearance in the ends of the cylinder may be contracted or expanded to meet the requirements of gases of varying qualities, it being well known that some gases require a higher degree of compression than others, in 70 which event the heads will be moved inward as required for contracting the clearing spaces. Thus, the cylinder may be adapted to gases of different grades, securing the highest efficiency from each. As a double 75 acting engine is here shown, this improvement is shown applied to each end of the cylinder, but obviously it is applicable to one end only of a single acting engine.

Paralleling cylinder 2 is the low pressure 80 cylinder 8, 9 being the piston therein and 10 the piston rod which, like rod 6 of the explosion cylinder, is connected to a crank of the shaft 11, carrying driving pulley 12. The valves for the explosion cylinder are operated 85 by shaft 13 geared at 14 to shaft 11, and a similar shaft 15, geared to the power shaft at 16, operates the valves for the low pressure cylinder.

The engine being double acting, the valve 90 mechanism at each end of the explosive cylinder is a duplicate of the other, and the same is true of the valves for opposite ends of the low pressure cylinder 8. At the end of explosion cylinder 2 is the inlet valve casing 17, 95 having its charge-admitting port 18 open at its inner end to cylinder 2 and at its outer end communicating with the vertical valve chamber 19, and also communicating with this chamber is the mixing chamber 20 from 100 which the charges of gas and air are drawn. The admission of these charges is controlled by the normally closed piston or spool valve 21, having its upper end connected to arm 22 mounted to swing vertically on fixed pivot 105 23. Movement for opening the valve is transmitted through rod 24, held normally depressed by spring 26. This rod rides on

cam 27 secured to shaft 13 which imparts upward movement thereto and to rod 24. Cam 27 is preferably formed in two parts which are independently adjustable on the shaft for varying the length of the lifting face of the cam, as may be required. This lifting mechanism operates with a governor mechanism, presently to be described, for timing the open periods of the inlet valve.

10 Beneath each of valve casings 17 is a valve casing 28 having its cylinder discharge port 29 opening into valve chamber 30, and extending from the latter is pipe 31 to inlet port 25 of low pressure cylinder 8, and also leading 15 therefrom is exhaust pipe 32 connected to the exhaust pipe 33 common to both cylinders. Within chamber 30 is the spool valve 34, the heads of which normally cover pipes 31 and 32. Stem 35 connects the valve with the 20 vertically swinging arm 36 which is held normally depressed by spring 37 with the cylinder outlet closed, as in Fig. 3. Arm 36 carries a horizontal roller 38, which rides on a group of cams 39 secured to shaft 13. This 25 group consists preferably of four cam sections, each provided with a neck or collar portion 40 carrying screw 41 for clamping to shaft 13. The cam sections are so adjusted with relation to each other as to divide the 30 periphery of the group into three parts of different radius. With the cam sections separately adjustable, the length of the face of each segmental part of different radius may be varied as conditions may require. When 35 part A of the smallest radius is uppermost and in engagement with roller 38, valve 34 is in lowermost position with exhaust 32 open. This occurs when the piston is making its exhausting stroke. The next higher radius B 40 holds the valve in neutral position, as in Fig. 3, with exhaust 32 and passage 31 to the low pressure cylinder closed, the valve being so held during the charging and compressing strokes of the piston and during the greater 45 part of the explosion stroke. During the latter portion of the explosion stroke, part C of largest radius comes into action and momentarily lifts the valve and admits the explosion charge, or rather the unexpended portion 50 thereof, into the low pressure cylinder, this momentary communication being shut off and communication with the exhaust opened as soon as the piston begins its exhausting stroke, discharging the products to 55 the atmosphere.

In the operation of explosive engines it is well known that unexpended energy remains at the completion of the explosion stroke. Instead of permitting this energy to be 60 wasted as heretofore, I conduct it to the low pressure cylinder where it has ample opportunity to act expansively on the low pressure piston and thus develop a very appreciable amount of power which is transmitted to the 65 drive shaft. A further feature incident to

this manipulation of the explosive energy is that the piston is relieved of back pressure at the beginning of its exhausting stroke.

At each end of low pressure cylinder 8 is valve casing 43 through which leads exhaust 70 port 44 to valve chamber 45, and from this chamber extends exhaust pipe 46 to the common exhaust 33. Exhaust valve 47 is preferably of the spool or balance type, with its stem 48 connected to vertically swinging arm 75 49, held normally raised by spring 50, with the exhaust closed. Arm 49 is depressed at the proper moment by cam 51 on shaft 15, thereby opening the valve and permitting the low pressure cylinder to exhaust. 80

For starting the engine, a pipe 52 extends to each of valve chambers 19, said pipe connecting with a source of air under pressure which may be shut off by valve 53. A valve 54 is provided in pipe 52 for each end of the 85 engine, each of said valves having a depending stem 55 adapted at its lower end to ride on a cam 56 secured to shaft 13. A spring 57 on the valve stem holds the valve normally depressed and closed. The valves are 90 so adjusted that with valve 53 open, air is passed to the cylinder ends at the proper moments for reciprocating the piston, valves 34 exhausting the air the same as when the engine is running normally. When by this 95 means the engine has acquired sufficient momentum, the explosive charges are admitted and the compressed air shut off.

No novelty is claimed for the governor mechanism heretofore referred to for controlling the open periods of the charge inlet valves. This mechanism is constructed and arranged as follows: Mounted on pivot 23, is the vertically swinging arm 60 to which the upper end of rod 24 is connected. Pivoted 100 to arm 60 is the downwardly forked latch 61 which is normally so held by spring 62 that its notched branch 63 is in engagement with a projection 64 on the rear face of arm 22, so that when arm 60 is raised, the valve connected arm 22 will also be raised, thus opening valve 21 for the admission of an explosive charge to the cylinder. The duration of this open period is determined by branch 65 of latch 61 which engages a shoulder 66 on the 110 pivoted arm 67, thus rocking latch 61 in opposition to spring 62, which results in the disengagement of branch 63 with projection 64, whereupon the valve is released and lowers to closed position. Arm 67 carrying shoulder 66 is connected to and moved by a governor mechanism, thus shifting the position of said shoulder with the varying speeds of the engine and causing latch 61 to release the valve after admitting an explosive charge 115 proportionate to the speed at which the engine is running, it being obvious that when at high speed the valve will be closed more quickly and the charge will be smaller than when running at low speed. The governor 120 125

here shown consists of a set of centrifugally acting balls 68, mounted on shaft 69 geared to shaft 13, the ball arms being connected to the vertically movable sleeve 70 to which is 5 pivoted the counterweighted lever 71, and at one end of this lever is head 72 from which extend links 73 and 74 to the valve controlling mechanisms at opposite ends of the cylinder. Also connected to sleeve 70 is lever 10 75 pivoted to stem 76 of the dash-pot piston 77, commonly employed in connection with this form of governor mechanism.

I claim:

1. The combination of a high pressure cylinder and piston of four-cycle type, a low pressure cylinder and piston, a valve casing having a valve chamber with a port extending to the center thereof from the high pressure cylinder, a pipe connecting one end of the valve chamber with the low pressure cylinder, an exhaust pipe leading from the other end of the valve chamber, a spool valve in the valve chamber with one head thereof adapted to cover the passage to the low pressure cylinder and with the other head covering the exhaust passage, means holding the valve with both of said passages closed during the charging, compressing and greater portion of the explosion strokes of the high pressure piston, means moving the valve to open communication with the low pressure cylinder during the latter portion of the explosion stroke, and means moving the valve to open communication between the high pressure cylinder and the exhaust only during the exhausting stroke of the high pressure piston.
2. The combination of a high pressure cylinder and piston of four-cycle type, a low pressure cylinder and piston, a valve casing having a vertically disposed valve-chamber, a spool valve movable longitudinally in said chamber, the chamber having a port extending from the center thereof to the high pressure cylinder, a passage from the low pressure cylinder communicating with the upper portion of the valve chamber and an exhaust port in the lower portion of the chamber, the said passage to the low pressure cylinder being closed by the upper head of the spool valve during the charging, compressing and

the greater portion of the explosion strokes of the high pressure piston, the lower head of the valve closing the exhaust port during all of said three strokes, means for raising the 55 valve during the latter portion of the explosion stroke for establishing communication with the low pressure cylinder, and means for lowering the valve to open the exhaust from the high pressure cylinder during the 60 exhausting stroke of the high pressure piston.

3. The combination of a high pressure cylinder and piston, a low pressure cylinder and piston with a communicating passage between the cylinders, an exhaust for the high 65 pressure cylinder, a spring-pressed valve controlling the said communication and exhaust, a valve operating shaft, and a plurality of cams adjustably secured to the shaft and operatively connected to the valve, 70 one portion of the cam surface holding the spring-pressed valve with said exhaust and cylinder communication closed, another portion of the cam surface moving the valve to establish communication between the cylinders, and another portion of the cam surface operating to establish communication between the high pressure cylinder and the exhaust. 75

4. The combination of a high pressure cylinder and piston, a low pressure cylinder and piston with a passage for establishing communication between the cylinders, an exhaust for the high pressure cylinder, a valve controlling said cylinder communicating passage and also said exhaust, a power shaft to which the pistons are connected, a valve-operating shaft adjacent the high pressure cylinder and geared to the power shaft, an operative connection between the valve-operat- 80 85 ing shaft and said valve for controlling said cylinder communication and said exhaust, an exhaust valve for the low pressure cylinder, and a shaft operatively connected to the last mentioned exhaust valve and geared to 90 95 the power shaft.

In testimony whereof I affix my signature in presence of two witnesses.

MICHAEL M. MAHER.
